CLOTHESPIN

Peter R. Dahlen, Twin Valley, Minn.

Filed Apr. 21, 1960, Ser. No. 60,273

Term of patent 14 years

(Cl. D17—3)

FIG. 1 is a perspective view of a clothespin showing my new design;

FIG. 2 is a front elevational view;

FIG. 3 is a side elevational view; and

FIG. 4 is a rear elevational view of the same.

I claim:

The ornamental design for a clothespin, as shown.
